CENTER PUNCHING ASSEMBLY

Noel J. Gouldsmith, Jr., Independence, Mo.

Application April 5, 1954, Serial No. 421,136

2 Claims. (Cl. 33—189)

This invention relates to center punching tools and, more particularly, to an improved center punching assembly adapted for use in work where an increased degree of accuracy and reliability is desirable.

It is the primary object of this invention to provide a center punching assembly having a work-engaging base provided with a peripherally marked perforation which may be aligned with great accuracy over the point to be punched by sighting through a magnifying lens forming a part of an upper structure swingably mounted on the base and carrying a reciprocable punching element adapted to extend concentrically through the perforation when the structure is swung from a viewing position to a punching position.

Other important objects of the invention, including significant details of construction, will be made clear or become apparent as the following description of the invention progresses.

In the accompanying drawing:

Figure 1 is a top plan view of the center punching assembly of this invention with the upper structure thereof disposed in its punching position relative to the base;

Fig. 2 is a cross sectional view taken on line II—II of Fig. 1 and showing in dotted lines the position of the punching element and the parts associated therewith when the same are reciprocated in a direction for accomplishing a punching operation;

Fig. 3 is a cross sectional view similar to that of Fig. 2 but showing the upper structure of the center punching assembly swung to its viewing or aligning position;

Fig. 4 is a view, partially in cross section and partially in elevation, taken on irregular line IV—IV of Fig. 2; and

Fig. 5 is a fragmentary, top plan view of that portion of the base in which the aligning and punching perforation is formed, particularly illustrating the alignment markings provided on the walls of such perforation.

Center punching by methods employing types of center punching tools heretofore known has been, at best, unreliable as to accuracy and subject in large measure to the experience and ability of the operator. The improved center punching assembly provided by this invention is not only simple in structure, inexpensive to manufacture and fool-proof in use, but further makes it possible for even inexperienced operators to accomplish center punching operations with greater accuracy and reliability than has heretofore been feasible in the case of experienced operators using conventional center punching tools.

Referring now to the accompanying drawing the numeral 10 broadly designates a base and the numeral 12 broadly designates an upper structure mounted on base 10 as hereinafter explained.

Base 10 comprises a metallic plate 14 having a work-engaging face 16 and a preferably flat, opposed face 18. In the embodiment of the invention shown for

2

purposes of illustration, face 16 is flat and thereby adapted for resting upon and being moved along a flat work surface. Obviously, however, face 16 could be arcuate or of any other configuration adapted to complement the work surface with which the assembly of this invention is to be used.

An aligning and punching perforation 20 is formed in plate 14 and preferably includes a chamfered portion 22 presenting a frusto-conical indicator surface 24 upon which a number of markings 26 are placed to aid in aligning the portion 28 of perforation 20 nearest face 16 of plate 14 concentrically with respect to a predetermined point on the work surface to be punched. A protuberance 30 extends laterally from face 18 of plate 14 and is provided with a bore 32 presenting a bearing for an elongated hinge pin 34 which extends beyond the extremities of bore 32 of protuberance 30. Plate 14 may also be provided, if desired, with a hole 36 for passing a screw (not shown), engageable in a threaded hole 37 of upper structure 12 for securing the latter in fixed relation to base 10 when the assembly is being stored, shipped or otherwise not being used.

Upper structure 12 includes a main body member 38 having a hollowed-out portion 40 and an elongated, cylindrical extension 42 provided with an external surface 44. A cylindrical bore 46 extends longitudinally through extension 42 and through main body 38 into communication with hollowed-out portion 40.

Main body portion 38 is provided with a base engaging surface 48 disposed in a plane preferably perpendicular to the axis of bore 46, such plane being spaced from the normally lowermost end 50 of bore 46. Main body 38 is also provided with a second base engaging surface 52 disposed within a plane intersecting the plane of surface 48 and forming an obtuse angle therewith.

Main body 38 includes side walls 54 and 56 each of which are perforated as at 58 to receive pin 34, thereby hingedly mounting structure 12 upon base 10 for swinging movement between a punching position placing surface 48 of main body 38 in engagement with upper face 18 of plate 14 and an aligning or viewing position placing surface 52 of body 38 in engagement with upper surface 18 of plate 14. It is noted that perforations 58 in side walls 54 and 56 are preferably located adjacent the zone of juncture between the planes of surfaces 48 and 52 in order to place the point of pivot of structure 12 upon base 10 to one side of the axis of bore 46.

A viewing opening 60 is formed in body 38 and has its axis preferably perpendicular to the plane of surface 52, an eye-piece 62 including a magnifying lens 64 being mounted in any suitable manner within opening 60.

Reciprocably mounted within bore 46 is an elongated punching element 66 having its lowermost end pointed as at 68 for indenting work to be punched. Slidably mounted upon surface 44 of extension 42 is a hollow, cylindrical cap 70 having an inner side wall surface 72 adapted to slide along surface 44 of extension 42 and an upper portion 74 provided with a bore 76 receiving the uppermost end of punching element 66, the latter being secured to upper portion 74 of cap 70 by means of a set screw 78. Disposed within cap 70 and bearing at its respective ends against lower portion 74 of cap 70 and the upper extremity of extension 42 is a coil spring 80 for yieldably biasing cap 70 and punching element 66 toward a position withdrawing element 66 from the upper extremity of extension 42. Punching element 66 is provided with a split ring stop means 82 adjacent its lowermost end to limit reciproca-
70 tion of element 66 under the influence of spring 80.

A suitable impact guard 84 may be provided, if desired, over the upper portion 74 of cap 70 for receiving pressure from the hand of an operator to reciprocate punching element 66 during operation of the assembly.

In operation, it will be clear that structure 12 is initially swung relative to base 10 to the position illustrated in Fig. 3 of the drawing, which disposes the axis of viewing opening 60 and lens 64 in concentric alignment with the axis of lower portion 28 of perforation 20. The operator, sighting through magnifying lens 64 and perforation portion 28, moves base 10 to a position exactly aligning the point on the work to be punched concentrically of perforation portion 28, as indicated by markings 26 provided on the indicator surface 24 of perforation 20. It may be noted that when mounting 12 is swung to the above-mentioned viewing or alignment position, light may freely pass between body 38 and plate 14 to render the work underlying perforation portion 28 visible to the operator; however, it will be obvious that auxiliary artificial lighting means within hollow portion 40 of body 38 could be provided in any conventional fashion, if desired.

When base 10 has been so aligned over the point on the work to be punched, plate 14 is held in position upon the work surface and upper structure 12 is swung on the pivot provided by pin 34 to the position illustrated in Fig. 2, which aligns the axis of bore 46 and accordingly the punching point 68 of element 66 concentrically with respect to the axis of perforation portion 28. It may be here noted that any conventional means of the adjustable screw or other suitable type might be provided on body 38 or plate 14 for assuring that the axis of bore 46 is exactly aligned with the axis of perforation portion 28, if desired; however, it is to be preferred that face 18 of plate 14 and surface 48 of body 38 be merely properly machined so as to align the axis of bore 46 with the axis of perforation portion 28 when body 38 is swung on pivot 34 to the position illustrated in Fig. 2.

With upper structure 12 in the punching position just described, the operator may exert appropriate pressure or impact force downwardly upon guard 84 which will slide cap 70 downwardly over extension 42 against the action of spring 80, thereby reciprocating punching element 66 along bore 46 and through perforation 20 moving punching point 68 of element 66 to a work-engaging position, as indicated in dotted lines in Fig. 2, slightly below face 16 of plate 14 to punch the work at the desired point.

It may be noted that bore 46 is preferably presented by a bushing 90 press fitted or otherwise suitably held in place within a larger bore 92 formed in body 38 and extension 42. Bushing 90 provides a wearing surface for slidably receiving reciprocable punch element 66 other than the casting by which body 38 and extension 42 are preferably formed, and may be replaceable, if desired.

It is also significant that edges 94, 96, 98 and 100 of plate 14 are preferably squared with each other and spaced predetermined distances from the center of perforation portion 28, in order that an edge 94, 96, 98 or 100 can be disposed along a line on the work to be punched and element 66 operated to indent a point on the work removed from said line by a distance equal to

the predetermined spacing of such edge from the center of perforation portion 28. Merely as an illustrative example, edge 94 may be one inch from the center of perforation portion 28, edge 96 may be one and one-half inches therefrom, edge 98 may be one and one-fourth inches therefrom and edge 100 may be one and three-fourth inches therefrom; it will be clear that, with such a construction, points may be accurately punched either one inch, one and one-fourth inches, one and one-half inches or one and three-fourth inches from a line on the work and, when parallel blocks (not shown), are also used, a point removed from either or both of a pair of perpendicular lines on the work by respective distances determined by the interposed blocks may be punched with great accuracy.

It will now be apparent that a center punching assembly of greatly improved accuracy and reliability has been provided. It will also be manifest that certain modifications or changes could be made in certain of the structure above described for purposes of illustration without departing from the true spirit or intention of this invention. Accordingly, it is desired that this invention shall be deemed limited only by the scope of the appended claims.

Having thus described the invention, what is claimed as new and desired to be secured by Letters Patent is:

1. A center punching assembly comprising a base plate having a work-engaging face, an opposed, flat face, and a viewing and punch-clearing perforation therethrough; a structure having a pair of contiguous surfaces disposed in obtusely angled planes, a viewing opening therethrough having its axis substantially perpendicular to the plane of one of said surfaces, and a punch-receiving bore therein having its axis perpendicular to the plane of the other of said surfaces; means swingably mounting the structure on the plate for movement between an aligning position and a punching position respectively disposing said one surface and said other surface in parallelism with said flat face of the base and said opening and said bore in axial alignment with said perforation; a magnifying lens mounted in said opening; a punch element; and means reciprocably mounting the element in the bore for movement to and from an operative position extending through said perforation when the structure is in said punching position.

2. In an assembly as set forth in claim 1, wherein a portion of said plate surrounding said perforation is internally chamfered to present a perimetric indicator surface on said plate in circumscribing relationship to said perforation, said surface being provided with index markings for use in centering the perforation upon a point on the work to be punched.
